PAPER DUST COLLECTING BAG FOR
VACUUM CLEANERS

Michael Sosnowich, Brooklyn, N. Y.

Application September 29, 1949, Serial No. 118,503

3 Claims. (Cl. 183—51)

1

This invention relates to new and useful improvements in discardable bags for use on vacuum cleaners.

More particularly, the present invention proposes the construction of an improved discardable bag for use on a vacuum cleaner, which is constructed of a porous or permeable sheet material for attachment to the discharge nozzle of an upright vacuum cleaner or similar type of vacuum cleaner having such a discharge nozzle, so that upon completion of a vacuuming operation the bag can be disconnected from the nozzle and thrown away when desired.

The use of the bag of the present invention provides the advantage of cleanliness and sanitation during use of the vacuum cleaner and particularly during clean out of the same; of warranting a trifling if not substantially negligible pricing of the new bag so far as the user of the vacuum cleaner is concerned, in view of the fact that the new bag is of such a nature that it may be fabricated in accordance with standard operations within the capacity of any of several rapid production automatic paper bag baking machines; and of incorporating in the bag a novel combination of elements for coating to give a markedly superior utility to the bag.

Especially in the case of a vacuum cleaner the aforesaid receptacle of which is present as a relatively rigid boxlike container, the discardable bag of paper or the like constituting the basic concept of the present invention may, if desired, be enclosed in a fortifying outer bag of cloth or the like, for protecting the therein contained discardable bag from being ruptured or damaged by abutment of any part thereof against sharp corners or the like incidental to operation of the cleaner.

The new bag is characterized by the inclusion of a main or ultimately collecting chamber subdivision, a minor subdivision alongside said main subdivision, said minor subdivision preferably of a kind describable as a fairly long tunnel of less cross-sectional area when distended than said main subdivision when distended; with such tunnel open at both ends yet dependably closable at that one of its ends adjacent to that end of said main subdivision where the latter, permanently closed at its other end, is openable and closable, whereby and by one operation the closable end of the tunnel and the said adjacent end of the main subdivision may both be closed by a single folding operation relative to the sheet material of which the bag is made. In combination with the foregoing, the parts of the bag are so arranged that, with that end of the tunnel which

2

is remote from the said foldingly closable end thereof fittable snugly on and about the discharge end of the vacuum cleaner's discharge nozzle for guiding into the interior of the latter the dust and dirt laden air stream, there is a specially located window, hole or opening, hereinbelow called the transfer port, between the tunnel and said main subdivision.

Another object of the present invention proposes the use of a clamp of any known ring type for securing the end of the tunnel in position on the discharge end of the discharge nozzle in a manner to prevent the force of the air discharging from the vacuum cleaner from blowing the tunnel off the end of the discharge nozzle.

A feature of the invention, further, is the provision of one or more tucks or pleatings extending along, and preferably along both sides, of the portion of the bag constituting said main subdivision; and, also, preferably along both sides of the portion of the bag constituting said tunnel.

The high-speed formation of such pleatings is also well within the capacity of an automatic paper bag making machine. The provision of said pleatings make it possible to produce a structure which throughout the same incorporates inherent protective means to reduce sudden shocks from air pressure in the bag, when, even where the bag is made of very lightweight and inexpensive kinds of paper material, the bag is inflated under high pressure. Moreover, the provision of said pleatings at the tunnel facilitate ready attachment of the tunnel to the discharge nozzle and by varying the number and lateral dimensions of the last-named pleatings various models of the new bag may be easily offered to the purchasing public with each such model particularly adapted for ideal fit-on relative to conduits differing as to external diameter and contour.

Similarly, and equally readily, various models of the new bag may be offered to the purchasing public, these different models having their aforesaid communication ports of differing areas and perhaps also at different locations along and intermediate the ends of the tunnel, so that each model is particularly adapted for optimum operation in connection with vacuum cleaners of different operating characteristics.

The invention further proposes the formation of an improved vacuum cleaner bag having a removable metallic sleeve arranged to be frictionally slipped into position over the discharge end of the discharge nozzle of the vacuum cleaner in a manner to connect the bag with the cleaner.

Still another object of the present invention

proposes a novel means for connecting the sleeve to the bag so that the sleeve can be conveniently disconnected from the bag leaving the bag and contents intact to be disposed of and permitting the sleeve to be connected with a fresh bag which is to be mounted on the vacuum cleaner.

It is a further object of the present invention to construct an improved discardable vacuum cleaner bag which is simple and durable, which is effective in use and which can be manufactured and sold at a reasonable cost.

For further comprehension of the invention, and of the object and advantages thereof, reference will be had to the following description and accompanying drawings, and to the appended claims in which the various novel features of the invention are more particularly set forth.

In the accompanying drawings forming a material part of this disclosure:

Fig. 1 is a bottom perspective view showing a now favored embodiment of the new discardable bag, distended as it would be while in use in a vacuum cleaner.

Fig. 2 is an enlarged longitudinal central sectional view taken on the line 2—2 of Fig. 1.

Fig. 3 is a further enlarged fragmentary detailed sectional view taken on the line 3—3 of Fig. 2.

Fig. 4 shows said bag when collapsed and in spread flat condition, as when in a package with a plurality of similar bags while in storage awaiting use.

Fig. 5 is a perspective view of the discardable vacuum bag constructed in accordance with a modification of the present invention.

Fig. 6 is an enlarged partial longitudinal sectional view taken on the line 6—6 of Fig. 5.

Fig. 7 is a sectional view taken on the line 7—7 of Fig. 6.

Fig. 8 is a perspective view of the apertured portion of the bag, per se, as used in the form of the invention shown in Figs. 5 to 7.

The discardable vacuum cleaner bag, according to the form of the invention shown in Figs. 1 to 4, includes a bag 10. The bag 10 is capable of being readily fabricated in an automatic paper making machine of standard type as already stated and comprises merely two substantially rectangular blanks of paper or the like, the larger blank for being folded and pasted to constitute a main subdivision 11 of the bag 10, and the smaller blank for being folded and pasted to constitute a minor subdivision or tunnel 12.

The pasting of larger blank is effected along overlapped marginal portions of its two sides, as indicated at 14 in Figs. 2 and 3; and also at one end of the structure made from the larger blank, at the flap 15.

Along the entirety of the length of each of the opposite sides of the main subdivision 11, the same is formed to include a fairly deep pleat 16; and the tunnel 12 is also pleated along the entirety of the length of each of its opposite sides. The tunnel is established by pasting together overlapped marginal side portions 17 of the blank from which it is folded, as indicated at 18.

The aforesaid communication port, this designated 19, is, as clearly shown in Figs. 2 and 3, provided by two like and matchingly arranged holes cut in the two blanks. The port 19 is established when the main subdivision 11 and the tunnel 12 are pasted together perimetrical of the holes. While this coat of paste preferably extends to the one end of the tunnel and hence almost to the end of the adjacent wall of the main subdivision

11, the other end of this paste application is preferably spaced a distance from the other end of the tunnel, for instance, continued down as far as the location indicated at 20 in Fig. 2, say to about one inch from the adjacent end of the port 19. Said coat of paste, however, is preferably coextensive in width with the width of the wall of the tunnel placed against the subdivision 11.

The tunnel 12 is of an internal diameter to have its free end slipped over the discharge end of the discharge nozzle of a conventional upright vacuum cleaner or other similar type of vacuum cleaner having such a discharge nozzle. The free end of the tunnel 12 is to be clamped to the discharge nozzle by any suitable ring-type clamp, not shown, so that the dust laden air will pass from the discharge nozzle of the vacuum cleaner, through the tunnel 12 and the port 19 and into the main subdivision 11 of the bag 10. The dust will be trapped within the bag 10 and the air will pass out through the pores of the porous material from which the bag 10 is formed.

It is of course understood that the end of the tunnel 12 and the adjacent end of the main subdivision 11 of the bag 10, opposite the flap 15, may be permanently closed at the time the bag is fabricated by the formation of a flap 21, or the flap may be held closed by any suitable clips of metal so that the bag may be opened after removal from the vacuum cleaner for inspection of the contents.

In the modification of the invention shown in Figs. 5 to 8, the discardable bag 10' is comprised of a main subdivision 11' and a minor subdivision or tunnel 12'. The tunnel 12' is constructed of metal and is removably attached to the main subdivision 11' to be removable therefrom so that the main subdivision 11', containing the dirt, can be discarded while the tunnel 12' is attached to another main subdivision.

The tunnel 12' is comprised of an inner sleeve 30 and an outer sleeve 31. Each of the sleeves 30 and 31 is formed at its inner end with a projecting flange 32. Secured to the adjacent faces of the flanges 32 there are resilient pads 33 of rubber or similar material.

The outer sleeve 31 has its inner end undercut and the free end of the inner sleeve is provided with threads so that the free end of the inner sleeve 30 can be screwed into the undercut portion of the outer sleeve for removably connecting the sleeves together. The relationship between the sleeves 30 and 31 is such that the inner peripheries of the sleeves will be flush when connected. This is important in that the interior of the connected sleeves 30 and 31 provide an unobstructed passage for the dirt laden air from the discharge nozzle of the vacuum cleaner to the interior of the main subdivision 11' of the bag 10'. The outer sleeve 31 should have an internal diameter corresponding to the outside diameter of the discharge nozzle of the vacuum cleaner upon which the bag 10' is to be used so that the tunnel 12' will frictionally retain its position upon the discharge nozzle of the vacuum cleaner, notwithstanding that air under pressure is being discharged into the bag 10'.

One side of the main subdivision 11' is formed with a hole 34 having a diameter corresponding to the outside diameter of the inner sleeve 30. Radiating from the hole 34 there is a plurality of slits 35, see especially Figs. 7 and 8. The slits have a length just very slightly less than the width of the flanges 32 of the sleeves 30 and 31, as shown in Figs. 6 and 7. The slits 35 per-

mit the size of the hole 34 to be expanded so that the flanges 32 of the inner sleeve 30 can be slipped into the interior of the bag with the free end of the inner sleeve 30 projecting from the bag to be connected with the outer sleeve 31. The material of the main subdivision 11' of the bag, surrounding the hole 34, will then be clamped between the adjacent faces of the resilient pads 33 to retain the slits 35 closed and the main subdivision 11' securely connected to the tunnel 12'. When the main subdivision 11' of the bag 10' is to be discarded, following use, the sleeves 30 and 31 are slightly separated so that the flange 32 of the inner sleeve 30 can be pulled from the interior of the main subdivision 11' so that the bag can be rolled up and discarded leaving the nozzle 12' intact to be used with another main subdivision 11'.

In other respects this form of the invention is similar to the previous form and like reference numerals identify like parts in each of the several views.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent, is:

1. A discardable bag for use on a vacuum cleaner comprising a main subdivision formed of porous material and a tunnel attached to said main subdivision for attachment to the discharge nozzle of the vacuum cleaner, said main subdivision being formed with a hole having slits radiating therefrom, said tunnel comprising an inner sleeve having an end portion of a diameter equal to that of said hole and projected through said hole, an outer sleeve threadedly engaged upon the extended end portion of said inner sleeve, and flanges radiating from the inner ends of said sleeves and engaging the inner and outer faces of the material of the bag about said hole.

2. A discardable bag for use on a vacuum

cleaner comprising a main subdivision formed of porous material, and a tunnel attached to said main subdivision for attachment to the discharge nozzle of the vacuum cleaner, said main subdivision being formed with a hole having slits radiating therefrom, said tunnel comprising an inner sleeve having an end portion of a diameter equal to that of said hole and projected through said hole, an outer sleeve threadedly engaged upon the extended end portion of said inner sleeve, and flanges radiating from the inner ends of said sleeves and engaging the inner and outer faces of the material of the bag about said hole, said flanges having a width slightly greater than the length of said slits.

3. A discardable bag for use on a vacuum cleaner comprising a main subdivision formed of porous material, and a tunnel attached to said main subdivision for attachment to the discharge nozzle of the vacuum cleaner, said main subdivision being formed with a hole having slits radiating therefrom, said tunnel comprising an inner sleeve having an end portion of a diameter equal to that of said hole and projected through said hole, an outer sleeve threadedly engaged upon the extended end portion of said inner sleeve, and flanges radiating from the inner ends of said sleeves and engaging the inner and outer faces of the material of the bag about said hole, and resilient pads mounted on the adjacent faces of said flanges and engaging the inner and outer faces of the material of said main subdivision surrounding said hole.

MICHAEL SOSNOWICH.
